UNITED STATES PATENT OFFICE.

GUSTAVE EGENOLF, OF NEW YORK, N. Y.

DEVICE FOR COVERING AND PROTECTING CHARGED RAILS.

No. 820,186.

Specification of Letters Patent.

Patented May 8, 1906.

Application filed November 25, 1904. Serial No. 234,274.

To all whom it may concern:

Be it known that I, GUSTAVE EGENOLF, a citizen of the United States, residing at New York city, county and State of New York, have invented new and useful Improvements 5 in Devices for Covering and Protecting Charged Rails, of which the following is a specification.

The object of this invention is to prevent 10 accidental contact with a charged rail, as also to protect the same from foreign matter, such as ice or other substance which might interfere with its function.

This invention can be applied without re- 15 quiring much change in the present structure and is set forth in the following specification and claims, and illustrated in the annexed drawings, in which—

Figure 1 is a sectional end elevation of a 20 rail with this invention applied. Fig. 2 is a side elevation of Fig. 1.

In the drawings is shown a rail *r*, known as a "charged" rail or so-called "third rail," provided with suitable spacing-blocks. These 25 rails are generally mounted on insulators or on blocks *s* of suitable material and held in place by well-known means, such as spikes or bolts or a suitable combination of fastening means.

30 In the ordinary construction of railroads, elevated roads, and the like a guard *t* is placed alongside the rails or track. Secured to such a guard is shown a bracket *k*. Said brackets carry arms or strips *i*, and a board 35 or shield *j* is carried by the arms supported by said brackets. This shield *j* lies underneath and extends longitudinally of the charged rail and prevents contact with such rail from underneath, as when workmen are 40 employed at the structure, as in painting or other matters. This shield or board being suitably extended between the rail-supports will prevent or to a great extent overcome 45 the danger of accidental contact with the charged rail supported over the shield. On the usual rail-guard *t* is shown a lateral guard or strip *g*, which tends to overcome danger of 50 accidental contact from one side. A lateral guard *h* at the opposite side also increases the safety. This lateral guard *h* is secured to the underlying shield.

A cover *a* is shown hinged to a lateral guard. A hinge *c* of usual cast-iron structure will answer. This cover can be formed by wooden sections joined by tongue and groove and secured to the hinge. A flange *d* acts as a stop to prevent the cover when closed from falling below the horizontal or onto the rail. This cover suitably overhanging the rail allows the shoe to contact or come to the rail from the side. The shoe or contact-arm *e* is secured by clamping portion *p* to links or slides *f*, connected to the carbody and allowing the shoe to drop or rest on the charged rail or conductor. The filling or leveling strips *m* and *o* can be added to the lateral guard *h*, if required, to bring the cover to the correct height or overhang as regards the charged rail. The hinges *c* can be suitably secured and firmly held in place by the 65 bolts *n*. The cover *a* and other parts, as strips *h* and *i*, can be made of wood or other suitable material. To avoid danger from sparks, it may be considered well to suitably fireproof or insulate certain parts by any 75 suitable fireproofing or insulating process.

What I claim as new, and desire to secure by Letters Patent, is—

1. A charged rail with supports therefor, a board or shield under the rail, a bracket for 80 supporting the shield, a strip made to rise from the shield, and a cover hinged to the strip and made to overhang the rail when closed.

2. A railroad structure comprising a rail- 85 guard, a bracket secured to the rail-guard, a shield carried by the bracket, a charged rail supported over the shield, a lateral guard for the charged rail secured to the first-named rail-guard, a lateral guard for the opposite 90 side of the charged rail and secured to the underlying shield and a cover hinged to a lateral guard and made to overhang the charged rail.

In testimony whereof I have hereunto set my hand in the presence of two subscribing 95 witnesses.

GUSTAVE EGENOLF.
